UNITED STATES PATENT OFFICE.

HENRI MATHIEU, OF PARIS, FRANCE, ASSIGNOR TO STE. DUFaux, MATHIEU & ANDRÉ, OF SAME PLACE.

DESIGN FOR A CLASP FOR CORSETS.

SPECIFICATION forming part of Design No. 20,023, dated July 15, 1890.

Application filed December 14, 1889. Serial No. 333,823. Term of patent 7 years. Patented in France October 1, 1889, No. 27,219; in Belgium October 2, 1889, No. 214; in England October 2, 1889, No. 1,344; in Switzerland October 17, 1889, No. 323, and in Germany November 1, 1889, XVI, 173.

To all whom it may concern:

Be it known that I, HENRI MATHIEU, a citizen of the French Republic, residing at Paris, France, have invented and produced a certain new and original Design for Clasps for Corsets, (which design has been registered in France, No. 27,219, on October 1, 1889; in Belgium, No. 214, October 2, 1889; in Great Britain, No. 1,344, October 2, 1889; in Switzerland, No. 323, October 17, 1889, and in Germany, Band 16, Blatt 173, November 1, 1889,) of which the following is a specification, reference being had to the accompanying drawings, forming a part thereof.

Figure 1 is a side elevation or edge view of a corset-clasp, showing my design. Fig. 2 is a front elevation of same.

a *b* represent the two corset-busks. *c* represents, as a whole, the element or part of the clasp on the busk *a*, and *d* represents, as a

whole, the element or part of the clasp on the busk *b*. The part *c* has a base of general triangular form with rounded corners and a rounded cup-like head *e*, the clasp presenting the appearance seen in Figs. 1 and 2. ²⁵

Having thus described my invention, I claim—

The design for a corset-clasp herein described, the same consisting of the part *c*, having a base of general triangular form with ³⁰ rounded corners, and having a rounded, eup-like head *e*, as set forth.

In witness whereof I have hereunto signed my name in the presence of two subscribing witnesses.

HENRI MATHIEU.
